UNITED STATES PATENT OFFICE.

CHARLES HENRY CROSSETTE, OF CHICAGO, ILLINOIS.

DESIGN FOR A NECKSCARF.

Specification forming part of Design No. 11,369, dated August 26, 1879; application filed July 29, 1879.
[Term of patent 3½ years.]

To all whom it may concern:

Be it known that I, CHARLES HENRY CROSSETTE, of Chicago, in the county of Cook and State of Illinois, have originated a Design for Neckscarfs, of which the following is a full, clear, and exact description, reference being had to the accompanying illustration or drawing, making a part of this specification.

A represents the neckband, and B B are the bosom flaps or pieces. C is the center-piece, representing the knot of a bow, and the parts B B have the appearance of being the ends of a broad scarf when tied in front in the form of a bow, the ends being pendent and crossing or partly crossing each other, and seeming to extend or hang from the sides or ends of the part or knot C. This appearance of a natural or genuine knot or bow is greatly aided or increased by the folds or gathers a a, which are made at the sides or lateral edges of the part C by carrying the upper ends of the parts B B slightly under or toward the said edges in such a manner that the parts so carried back shall tie or seem to tie underneath the parts which overlap the center-piece or knot C, as is clearly indicated in the drawing. These folds or gathers a a are essential features of my design, and they perform no service or function in the construction of the scarf, and in no way add to its utility, but are employed only as features of form or configuration to give the appearance already described.

What I claim as my invention is—

The design for a neckscarf in which the upper parts of the bosom-flaps are folded or gathered in along or near the vertical edges of the center-piece or knot, as shown at a a in the accompanying illustration, and substantially as hereinbefore described.

CHARLES HENRY CROSSETTE.
